UNITED STATES PATENT OFFICE.

JAMES E. SMITH, OF WILKINSBURG, PENNSYLVANIA, ASSIGNOR OF ONE-HALF TO
ISAAC GORDON, OF PITTSBURGH, PENNSYLVANIA.

PROCESS AND APPARATUS FOR FORMING GRIDS.

Application filed January 19, 1923. Serial No. 613,627.

My invention relates to a process and apparatus for forming grids and has for its object to form sheets of any desired material into grid-like structures by punching or stamping.

Other and further objects of my invention will be apparent from the following description and from the accompanying drawings of one embodiment thereof, in which Figure 1 is a general plan of one type of apparatus;

Figure 2 a section on line 2—2 of Figure 1 looking in the direction of the arrows but omitting the base plate;

Figure 3 a section on line 3—3 of Figure 2 looking in the direction of the arrows;

Figure 4 a plan of a completed grid of the type chosen for purposes of illustration;

Figure 5 a section on line 5—5 of Figure 4 looking in the direction of the arrows;

Figure 6 a vertical section through a perforating unit showing the perforating blades in elevation;

Figure 7 a vertical section through an upper die unit showing die members in elevation;

Figure 8 a vertical section through an upper holding unit showing a partition in elevation;

Figure 9 a vertical section through a lower holding unit showing a partition in elevation;

Figure 10 a vertical section through a lower die unit showing die members in elevation;

Figure 11 a side elevation of a base and guide rods;

Figure 12 a bottom view of a perforating unit showing the perforating blades;

Figure 13 a bottom view of an upper die unit showing the die members;

Figure 14 a bottom view of an upper holding frame showing partitions; and

Figure 15 is an enlarged view of the section illustrated in Figure 3.

Similar reference characters refer to similar parts throughout the drawings.

For purposes of illustration the invention has been described in connection with a grid for storage batteries. It has been necessary heretofore to manufacture grids of the type illustrated largely by casting, as it has not been possible to withdraw stamps or punches in a stamping operation without

destroying or distorting the bars forming the grid members. I have discovered a process and apparatus by which such grids can be formed by punching or stamping, one embodiment of which is as follows:

A pair of holding units (Figures 8, 9, and 14) is adapted to hold the grid forming material during the stamping and punching operation. In the present embodiment each unit comprises a frame 1 provided with partitions 2 having spaces 3 therebetween and preferably is provided with a supporting edge 4 having holes 5 for the passage of aligning guide rods.

On each side of the holding units is a die unit (Figures 7, 10, and 13) each of which comprises die members 11 and 12 with a space 13 therebetween. Cooperating edges of opposite die members may be of any desired shape or length, the embodiment illustrated showing the die member 11 with a flat operating face adapted to cooperate with an opposing die member 12 having a V-shaped face, so that the resultant grid consists of triangular shaped ribs 43 and 44 (Figures 4 and 5). The die members preferably are mounted on a supporting plate 14 having holes 15 therein for the passage of aligning guide rods. The die members are adapted to pass into the sheet of material through spaces 3 in the holding units.

On one side of one of the die members is provided a perforating unit (Figures 6 and 12) comprising a series of perforating blades 21 mounted on a supporting plate 22 having holes 23 for the passage of aligning guide rods. Blades 21 are adapted to pass through the spaces 13 between the die members 11 and 12.

The various units may be mounted on a base 31 (Figure 11) having guide rods 32 adapted to pass through holes provided in each member in order to align and keep the parts in proper position.

In operation the sheet of grid forming material is placed between holding frames 1 by means of which it is clamped in position. Die members 11, 12 then may be operated to form grid bars 43, 44 after which perforating blades 21 are forced through the spaces provided therefor to remove the material between the grid bars. The perforating blades then are removed, next the die members, and then the holding plates to re-

lease the grid. In this manner the various operating parts are withdrawn from the plate without any distortion or bending thereof. The plate formed by this embodiment is similar to that shown in Figure 4 of the drawings comprising a grid frame 41 with partitions 42 between which run ribs 43 and 44 with spaces 45 therebetween.

When a sheet of ductile material such as 10 lead, is subjected to pressure between the die units, the lead between the rib forming die members or surfaces 11 and 12 is compressed to the desired thickness corresponding to the height of one rib. By reason of the 15 alternate spacing of the rib-shaping members 12 and the flat-face anvil or rib-backing members 11, the ribs formed are disposed in staggered relation. The alternate ribs are formed on opposite sides of a plane 20 intermediate the original surfaces of the lead sheet. The excess material, due to its ductility, is forced to flow, by a combined lateral and vertical movement, into the spaces 13 between the die members 11 and 25 12 to form slugs perpendicular to the plane of the original sheet of lead and extending on opposite sides of the plane intermediate the original surfaces.

While forming grids by the method and 30 apparatus which I have herein described, I have found that when the proper amount of pressure is applied, the slugs of excess material will be joined to the rib structure by a very thin ribbon of the lead and are readily 35 and easily removed by slight pressure of the blades 21. In some instances mere pressure of the fingers has sufficed to remove the slugs.

After the slugs of excess material are 40 removed, the rib structure remains, as is illustrated in Figs. 4 and 5. The ribs are formed in series between the partitions or crossbars 42. The arrangement of each section between the adjacent crossbars 42 is similar.

45 As may be seen from Fig. 5, the bases of the ribs are substantially aligned in a plane intermediate the original surfaces of the lead sheet from which the grid was formed. The resulting structure that is thus obtained is desired in order that the paste or active material for the grid may be supported as a unit by the ribs between successive partitions or 50 crossbars 42. The tendency of the paste to crack and separate between adjacent ribs is thus obviated.

Although the ribs are herein illustrated as triangular or substantially so, any contour will suffice which will permit ready withdrawal from the shaping surfaces of the dies. For this reason a non-rectangular contour having a larger base dimension than 55 top dimension is desirable.

It is contemplated that one or a plurality of grids may be stamped out at the same 60 time.

Many modifications of my invention will be apparent to those skilled in the art without departing therefrom or from the scope of the claims, my invention not being limited to the particular embodiment chosen for 70 purposes of illustration, but comprising a process and apparatus for forming grids from a sheet of grid forming material by a stamping or punching operation without distortion or bending of the formed grid. 75

What I claim and desire to secure by Letters Patent is:

1. The process of forming a grid which comprises clamping a sheet of grid forming material between substantially flat holding frames having spaces therein for the passage of grid forming members, passing grid forming means through the spaces in said holding frames to form a completed grid from said material at one operation and while the grid is clamped in said holding frames, retracting the grid forming means from the completed grid while the grid still is held by said holding frames, and then releasing the completed grid from said holding frames.

2. The process of forming a grid which comprises stamping up a series of ribs between oppositely positioned dies having spaces therebetween, passing metal removing blades through said spaces while the dies are in contact, and retracting the metal removing blades and the dies.

3. The process of forming a grid which comprises clamping a sheet of grid forming material between holding frames having spaces therein, stamping up a series of ribs in said material by a plurality of cooperating die members passing through said spaces and provided with spaces between die members, passing metal removing blades through the spaces between said die members, and removing said blades, dies, and frames from the grid.

4. The process of forming a grid which comprises die stamping and metal punching a sheet of grid forming material to desired shape while held in position by clamping frames, and then removing first the metal punches, next the dies, and last the clamping frames.

5. In an apparatus for forming grids, clamping frames adapted to hold a sheet of grid forming material therebetween and having spaces for the passage of die members, cooperating die members adapted to pass through the spaces in said frames to form ribs in said material and provided with spaces between die members, and material removing blades adapted to pass through spaces between said die members to remove the material between ribs.

6. In a grid forming apparatus, means to form a grid by a stamping operation comprising clamping frames adapted to hold a 130

sheet of grid forming material therebetween and having spaces for the passage of die members, and cooperating die members adapted to pass through said spaces to form 5 ribs in said material.

7. In a grid forming apparatus, means to form a grid by a stamping operation comprising clamping frames adapted to hold a sheet of grid forming material therebetween 10 and having spaces for the passage of die members, and material removing blades adapted to pass through said spaces to leave ribs in said material.

8. In a grid forming apparatus, means to form a grid by a stamping operation comprising cooperating die members adapted to form a rib in a sheet of grid forming material and provided with spaces between die members, and material removing blades 20 adapted to pass between spaces between die members to remove material between ribs.

9. The method of forming a grid for a storage battery which comprises compressing a sheet of ductile material to form the 25 outline of a structure embodying elements staggered relative to a middle plane of the material and simultaneously to cause excess material to flow into spaces bound by planes perpendicular to the sheet of material and 30 limited by the adjoining structural elements, and then expelling all excess material so formed.

10. The process of forming a staggered-rib battery grid which consists in compressing a 35 sheet of lead to form the ribs and causing the excess metal to flow into spaces between the ribs, and then removing such excess metal.

11. The process of forming a staggered-rib battery grid which consists in compressing a 40 sheet of lead to form the staggered ribs as desired for the completed grid and expelling the excess metal into solid slugs between the ribs, and then removing such slugs.

12. The process of forming a battery grid which consists in compressing a lead blank 45 between two cooperating dies provided with offset alternate die and backing members to form the ribs desired for the completed grid and then removing the excess material.

13. The method of making a storage battery grid of the staggered rib type which comprises compressing a sheet of lead to 50 form the desired final grid structure and to expel all excess lead into slugs joined to the grid structure by a thin ribbon of lead, and then removing the slugs so formed.

14. The method of forming a grid for a storage battery, which comprises compressing a blank sheet to form separate distinct 55 spaced webs alternately extending inwardly from opposite sides of the blank sheet, simultaneously expelling excess material adjacent the ribs in a lateral direction to form slugs between the ribs and bound thereto

by relatively thin portions, and then removing said slugs from the ribs.

15. A machine for making battery grids of the staggered-rib type from sheet lead comprising two movable die members adapted 70 to form upon the sheet of lead the outline of the final desired grid structure, means for removing excess material from between rib outlines, and means for aligning the die members with each other and the excess 75 metal removing means with the die members.

16. A grid forming machine, comprising two cooperating die members provided with a plurality of rib-forming recesses of substantially V-shape and with cavities between 80 said recesses, the recesses in each member being staggered relative to the recesses in the other and the cavities of both members registering.

17. A grid forming machine comprising 85 means provided with compression surfaces for engaging a blank from which the grid is to be formed, to preclude lateral movement thereof, and two co-operating die members provided with rib-forming surfaces for 90 forming staggered ribs alternately extending from a plane substantially intermediate the opposite side surfaces of the blank.

18. A grid forming apparatus comprising two cooperating die members for engaging a blank from which the grid is to be formed, said die members being severally provided with alternate rib-forming and 95 rib-backing elements and adapted for registry whereby the rib-forming element of one 100 die member registers with the rib-backing element of the other die member, and means for maintaining such registry.

19. A battery grid forming apparatus comprising two compression members severally provided with alternate rib-forming and 105 rib-backing portions, means for aligning the rib-forming portions of each compression member with the rib-backing members of the other compression member, and means for removing the excess material between the 110 formed ribs.

20. A battery grid forming apparatus comprising two die members respectively provided with alternate rib-forming recesses 115 and rib-backing portions, means for maintaining the die members in predetermined operative relation whereby a lead blank may be compressed therebetween to have a plurality of groups of staggered ribs, and means 120 for removing the metal between the ribs so formed.

21. An apparatus for forming storage battery grids from lead sheet comprising two 125 cooperative die members for forming a plurality of ribs in staggered relation, alternate ribs occupying space between a plane of one surface of the sheet lead and a plane intermediate the planes of both surfaces, means for maintaining the dies in predetermined 130

- operative relation, and means operative after the formation of the ribs for removing metal between the ribs to present a latticework for receiving and supporting paste or active material.
5. 22. An apparatus for forming storage battery grids from lead sheet comprising two cooperating die members for forming or outlining a battery grid of the staggered-rib type, and a movable member for removing excess material between the successive ribs so formed.
10. 23. A machine for making storage battery grids from sheet material, comprising two cooperating die members provided with means for compressing a sheet blank into predetermined rectangular shape consisting of a plurality of rectangular sections separated by bars of the same thickness as the original blank, and spaced series of webs extending perpendicularly between such bars, each alternate series occupying space between opposite side surfaces of the original blank and a plane intermediate said surfaces.
15. 24. A machine of the character described in claim 23 comprising the said die members which operate, while forming the series of webs, to physically displace all excess material adjacent said webs to form slugs between said webs perpendicular to the plane of the blank, and means operative after the

formation of said slugs for expelling them to leave the grid of desired form.

25. A machine of the character described in claim 24 comprising the die members of the character described, the means for expelling the excess material, and means for controlling proper operative relation between the die members and the expelling means.

26. A grid forming machine comprising two cooperating die members, each die member embodying a plurality of spaced web forming surfaces and straight anvil or backing surfaces intermediate successive web forming surfaces and spaced therefrom by openings adapted to receive excess material.

27. A grid forming machine comprising two cooperating die members, each die member embodying a plurality of spaced web forming surfaces and straight anvil or backing surface intermediate successive web forming surfaces and spaced therefrom, and means for aligning the die members in predetermined operative relation whereby web forming surfaces of each die member are aligned and cooperate with anvil or rib-backing surfaces of the other die member.

In testimony that I claim the foregoing, I have hereunto set my hand this second day of January, 1923.

JAMES E. SMITH.
